UNITED STATES PATENT OFFICE

DELOS HOLDEN, OF EAST ORANGE, NEW JERSEY, ASSIGNOR, BY MESNE ASSIGNMENTS, TO NEW JERSEY PATENT COMPANY, OF WEST ORANGE, NEW JERSEY, A CORPORATION OF NEW JERSEY.

PHONOGRAPH OR TALKING MACHINE.

1,170,258.

Specification of Letters Patent. Patented Feb. 1, 1916.

Application filed July 14, 1913. Serial No. 778,824.

To all whom it may concern:

Be it known that I, DELOS HOLDEN, a citizen of the United States, and a resident of East Orange, in the county of Essex and State of New Jersey, have invented certain new and useful Improvements in Phonographs or Talking-Machines, of which the following is a description.

My invention relates to phonographs or talking machines and more particularly to phonographs or talking machines of the cabinet type having a movable cover which contains the usual horn or sound amplifier.

The principal object of my invention is to provide an improved device of this character having one or more covers which may be opened or closed without forming a break in or interrupting the continuity or varying the length of the sound conveying passage or passages through which the sound waves from the reproducer pass to the atmosphere, the generic invention and one species thereof being claimed in an application, Serial No. 763,702 filed by me on April 26, 1913 and entitled phonographs or talking machines. In this application I shall describe and claim another species of the invention.

In order that the invention may be more clearly understood, attention is hereby directed to the accompanying drawing forming a part of this specification and in which—

Figure 1 is a view partly in vertical section and partly in elevation showing a talking machine embodying a form of my invention comprising a plurality of covers and amplifiers, the covers being shown in open position in dotted lines; Fig. 2 is a view of the same partly in plan and partly in horizontal section; and Fig. 3 is a view similar to Fig. 2 of a talking machine containing another embodiment of my invention.

In all the views like parts are designated by the same reference numerals.

Referring to the drawing and more particularly to Figs. 1 and 2 thereof, the cabinet shown comprises a base or body portion 1 and hollow covers 2 pivotally supported in a manner hereinafter more fully described. A horizontal partition plate or other similar support 3 extends across and is secured in any suitable manner to the top of the

body portion 1 of the cabinet, the partition plate supporting on its lower side a casing 4 which incloses a motor (not shown) for 55 rotating the turntable or support 5 upon which the sound record 6 to be reproduced is adapted to be supported. A reproducer 7 arranged for operation on the record 6 communicates with and is carried by a tapered 60 sound conveying arm 8 which is provided at its rear with a downwardly extending portion communicating with and pivotally supported by a tubular sound conveying member 9. The sound conveying member 9 65 is stationary and may be secured to the cabinet in any suitable way, as by means of brackets 10. The said member 9, in the form of my invention shown in Figs. 1 and 2, extends transversely of the cabinet from 70 one side to the other and is preferably of increasing cross section from the point at which the sound waves from the reproducer are discharged into the same by the arm 8 toward its opposite ends at the sides of the 75 cabinet. The ends of the sound conveying member 9 are provided with forwardly extending outlet portions 11, the axes of which are parallel and are located at the intersection of the top surface of the support 3 and 80 the outer surfaces of the side walls of the cabinet. Each of the covers shown in Figs. 1 and 2 comprises a side wall 12, a rear wall 13, and a top wall 14, the inner edges of the top and rear walls of one cover being 85 adapted to contact with the corresponding edges of the top and rear walls of the other cover when the covers are closed, as shown in Fig. 1. Each cover incloses and has secured thereto in any suitable manner a sound amplifier 15, the mouth of which is located in the open front portion of the cover, the small end of each amplifier extending in axial alignment with one of the portions 11 90 of the sound conveyer 9. The sound conveyers are so connected to the parts 11 as to permit raising or lowering of the covers and the amplifiers connected thereto without forming a break in or interrupting the continuity or varying the length of the sound 95 passage at the points where the same are connected. Each part 11, as shown, is provided with a portion 16 fitting within the smaller end of the amplifier with which it communi- 100

cates, the amplifier bearing against a circular collar 17 on the part 11. A rod 18 having headed ends bearing respectively against the rear end of the part 11 and a bracket 19 in the amplifier serves to hold each amplifier in proper position with respect to the sound conveyer 9 and the corresponding cover in proper position with respect to the base of the cabinet.

10 The device disclosed in Fig. 3 differs from that disclosed in Figs. 1 and 2 only in that a single cover 2' carrying a single amplifier 15' is employed in place of the two covers and amplifiers shown in Figs. 1 and 2, and 15 in that the stationary sound conveying member 9' with which the arm 8 communicates extends only to one side of the cabinet, the connection of the same with the sound amplifier being identical with that disclosed for each amplifier in Figs. 1 and 2. The 20 single cover of the device disclosed in Fig. 3 will, of course, have two side walls, whereas the covers of the device of Figs. 1 and 2 have but a single side wall.

25 In both forms of the invention herein disclosed, each cover and the sound conveyer movable therewith are mounted for pivotal movement about the same horizontal axis, which latter coincides with the center or axis of the tubular member 11 and the smaller end of the amplifier and with the axis of the rod 18. There is a continuous sound conveyer of fixed or uniform length extending from the reproducer to the exit of 30 the amplifier regardless of the position of the cover or covers, the amplification due to the tapering of the sound conduit beginning at a point adjacent the reproducer and continuing gradually to the exit of the sound 35 conveyer. The reproducer and the record support are adapted to remain in operative relation to each other regardless of the position of the cover.

40 It is understood that my invention is not limited to the precise apparatus shown, but may be varied within the scope of the appended claims without departing from the spirit of my invention.

Having now described my invention, what 45 I claim as new and desire to secure by Letters Patent is as follows:

50 1. In a phonograph or talking machine, the combination of sound reproducing apparatus, a pivoted cover therefor, and a sound amplifier movable with said cover and connected with said sound reproducing apparatus, the pivotal axis of said cover passing through the axis of the smaller end of 55 said amplifier and extending lengthwise of the exit portion of said amplifier, substantially as described.

60 2. In a phonograph or talking machine, the combination of a record support, a reproducer in operative relation thereto, a plurality of covers for said reproducer and record

support movable about different axes, each of said covers having a sound amplifier movable therewith, and sound conveying means connecting all of said amplifiers with said reproducer, substantially as described.

65 3. In a phonograph or talking machine, the combination of sound reproducing apparatus, a pivoted cover therefor, a sound amplifier movable with said cover, and a fixed tubular member communicating with 70 said sound reproducing apparatus and said amplifier, the pivotal axis of said cover and amplifier being coincident with the axis of the exit portion of said fixed member and extending lengthwise of the exit portion of 75 said amplifier, substantially as described.

80 4. In a phonograph or talking machine, the combination of a rotatable record support, a reproducer in operative relation thereto, a movable cover for said record support and reproducer, a movable sound conveying arm connected with said reproducer, a sound amplifier movable with said cover about an axis extending lengthwise of the 85 exit portion of the amplifier, and a stationary sound conveying connection between said arm and said amplifier, said amplifier and sound conveying connection being of fixed length and in direct and uninterrupted communication during the opening and 90 closing of said cover, substantially as described.

95 5. In a phonograph or talking machine, the combination of a horizontal record support, a reproducer in operative relation thereto, a plurality of sound amplifiers movable about substantially horizontal axes which are out of alignment with the axes of the exit portions of said amplifiers, and sound conveying means connecting all of 100 said amplifiers with said reproducer, said sound amplifiers being in direct and uninterrupted communication with said sound conveying means during the movement of said amplifiers about said axes, substantially as 105 described.

110 6. In a phonograph or talking machine, the combination of a record support, a reproducer in operative relation thereto, a plurality of covers for said reproducer and record support movable about spaced substantially parallel axes, each of said covers having a sound amplifier movable therewith, and sound conveying means connecting all of 115 said amplifiers with said reproducer, substantially as described.

120 7. In a phonograph or talking machine, the combination of a record support, a reproducer in operative relation thereto, a plurality of movable covers for said reproducer, a sound amplifier movable with each cover and sound conveying means connecting all of 125 said amplifiers with said reproducer, said sound amplifiers being in direct and uninterrupted communication with said 130

sound conveying means during the opening or closing of said covers, substantially as described.

8. In a phonograph or talking machine, the combination of a record support, a reproducer in operative relation thereto, a plurality of pivoted covers for said reproducer and record support, a sound amplifier movable with each cover, and sound con-

veying means connecting all of said amplifiers with said reproducer, the pivotal axis of each cover extending lengthwise of the exit portion of the amplifier movable with said cover, substantially as described.

15 9. In a phonograph or talking machine, the combination of a record support, a reproducer in operative relation thereto, a plurality of pivoted covers for said reproducer and record support, a sound amplifier movable with each cover, and sound conveying means connecting all of said amplifiers with said reproducer, the pivotal axis of each cover extending lengthwise of the exit portion of the amplifier movable with 20 said cover, and being coincident with the axis of one of the exits of said sound conveying means, substantially as described.

25 10. In a phonograph or talking machine, the combination of record supporting means, sound reproducing means in operative relation thereto, a plurality of movable covers

for said sound reproducing means, sound amplifying means movable with each cover, and sound conveying means connecting said sound amplifying means with said sound reproducing means, said sound amplifying means being in direct and uninterrupted communication with said sound conveying means during the opening or closing of said covers, substantially as described. 35

40 11. In a phonograph or talking machine, the combination of sound reproducing apparatus comprising a reproducer, a pivoted cover for said sound reproducing apparatus, said sound reproducing apparatus being operative for both open and closed positions of said cover, and sound conveying means connected with said reproducer and comprising a sound amplifier movable with said cover, the pivotal axis of said 45 cover extending lengthwise of the exit portion of said amplifier, and said sound conveying means being of fixed length and free from breaks or interruptions throughout its length during the opening and closing of the cover, substantially as described. 50

55 This specification signed and witnessed this 10th day of July 1913.
